Primary Examiner — Cynthia Ramirez(74) *Attorney, Agent, or Firm* — Troutman Sanders LLP**(57) CLAIM**

I claim the ornamental design for a portable carrier, as shown and described.

DESCRIPTION

FIG. 1 is a right front perspective view of a portable carrier showing my new design;

FIG. 2 is a front elevational view of the portable carrier shown in FIG. 1;

FIG. 3 is a rear elevational view of the portable carrier shown in FIG. 1;

FIG. 4 is a left side elevational view of the portable carrier shown in FIG. 1;

FIG. 5 is a right side elevational view of the portable carrier shown in FIG. 1;

FIG. 6 is a top view of the portable carrier shown in FIG. 1; and,

FIG. 7 is a bottom view of the portable carrier shown in FIG. 1.

The broken lines in the figures are environmental only and form no part of the claimed design.
